UNITED STATES PATENT OFFICE.

THEOPHILUS CHARLES EBERHARDT, OF CUERO, TEXAS.

ADDRESSING-MACHINE.

SPECIFICATION forming part of Letters Patent No. 375,481, dated December 27, 1887.

Application filed April 23, 1885. Serial No. 163,138. (Model.)

To all whom it may concern:

Be it known that I, THEOPHILUS CHARLES EBERHARDT, a citizen of the United States, residing at Cuero, in the county of DeWitt and 5 State of Texas, have invented certain new and useful Improvements in Addressing-Machines; and I hereby declare the following to be a full, clear, and exact description thereof, reference being had to the accompanying drawings, 10 forming part of this application, wherein—

Figure 1 is a perspective view of the entire machine. Fig. 2 is a central vertical sectional view. Fig. 3 is a detail side view showing the gearing of the feed-rolls. Fig. 4 is a detail 15 side view taken from the opposite side, illustrating the main wheel and its attachments. Fig. 5 is a detail front view showing the cutting-knives, feed-rolls, &c. Fig. 6 is a detail view, partly in section, of the movable plate, 20 its guides, and the paste-roll. Fig. 7 is a detail view of the paste-roll and its attachments with the movable plate. Fig. 8 is a detached view of the corrugated roller O, its axle and gear-wheel.

25 My invention relates to that class of addressing-machines which paste, cut, and attach the slip simultaneously, or with one operation.

My object is to obtain an addressing-machine which can be operated with neatness 30 and dispatch, and at the same time will be strong and simple, as will be hereinafter more specifically described in the specification and pointed out in the claims.

Referring to the drawings, A is the metallic 35 frame which supports the device, and to which is secured the oval tube B.

C is the sliding tube, which incloses tube B, and it is held in place by the rear support, C', which slides in ways or guides Z in the rear 40 of the frame, and carries the movable cutter X and the arm Y Y'. Within the tube B is a flat hollow guide, D, which conducts the printed slip from the spool or drum down to the feed-rolls, where it is pasted, cut, and applied.

D' is the printed slip or paper ribbon containing the addresses, which is first wound around the spool, the free end being carried 45 down to the rolls I, R, and O.

G represents the flat table or rim secured to or made integral with the top of the tube B, and having an arm, F, bent up at a right an-

gle to support the spool, which is provided with the sides F' and the winch or handle F''.

H is a tension-screw provided with a spring 55 on one of the sides F', which prevents undue rotation of the spool.

I is a feed-roll, between which and the felt paste-distributing roll R the paper slip is drawn to receive the paste.

J is another and fluted feed-roller, which, in conjunction with feed-roll I, delivers the pasted slip to the cutters. The feed-rolls O and I and the paste-cock P² are journaled in the sides of frame A and gear with each other by gear-wheels i P o.

The tube B is divided by the guide D into two parts, which are filled with paste or its equivalent, and the paste is fed to the distributing-roll R through the gate Q, regulated 70 by the flanged paste-cock P².

C¹ is a spiral spring wound around the tube B and secured by its ends abutting against the top of the frame and the lower surface of plate G'. The plate G', at the lower end of the sliding 75 tube C, is provided with a projecting arm, C', which carries a pin, C³, whose lower projection is regulated by a screw-thread, which pin, as the tube C is forced down on the tube B, abuts against the upper side of the projection M, mounted on the axle or shaft of the wheel J and attached to and made part of the clutch K by the arm L and turns the clutch, and at the upward movement of the sliding tube C, made through the agency of the 80 spring C¹, the arm Y Y' strikes against the under side of the projection M and partly turns the wheel J, and with it the several rollers I, O, and R and the paste-cock P², through their gear attachments. As the lower projection of 85 the screw-threaded pin C³ is shortened or lengthened by said pin C³ being screwed up or down the arm L, to which is attached the clutch K, is, by pressing the sliding tube C downward, more or less depressed, thus causing the clutch K to be moved over a shorter or longer space in the downward movement of the arm L.

Now, since the clutch K is so constructed that by the upward movement of its arm L it (the said clutch K) will engage itself 90 on the inside periphery of the wheel J, it follows that while the sliding tube C, with its plate C' and its upper projecting arm, C², and its lower projecting arm, Y Y', is moved up- 95 100

ward and returned to its normal position by the agency of the spiral spring C¹, the projection M on the arm L being struck by the projecting arm Y Y', the arm L is returned to its 5 normal position, and by the agency of the clutch K causes the wheel J, with the rollers I, O, and R and the paste-cock P², to make such part of the revolution as is equal to the part of the revolution the clutch K made on 10 the inside periphery of the wheel J, while the arm L, with its projection M, was being pressed downward by the screw-threaded pin C³ in its descent, thus causing the wheel J, with its rollers I, O, and R and the paste-cock P², to 15 revolve more or less at each upward movement of the sliding tube C as the screw-threaded pin C³ has been previously screwed up or down. By this means—that is, by screwing the screw-threaded pin up or down—the travel of 20 the wheel J, with its rollers I, O, and R, at each depression of the sliding tube C can be made to conform exactly to the length of the address printed on the addressed slip, which is fed to the cutting-knives by the feed-rollers I and R. 25 U² are the springs, by means of which the paste-roll is held against the ribbon passing between it and roll I.

T is a removable plate sliding in ways in the arms U and carrying the paste-roll. The 30 springs U² press against the arms U, and the latter have rigidly secured to them the curved arms U', which move in slots V in the frame and have at their rear ends notches to receive the ends of the spindle O' of the roller O. The 35 arms U, by means of springs U² and arms U', allow the roller R to approach to or recede from the main roll I.

The main wheel J is journaled at one end of the axle I' of the feed-roll I which carries at its other end the gear-wheel i, meshing with the gear-wheels P and o on the paste-cock and the corrugated roll, respectively, and said wheel J is sustained by a support, N, attached to the frame, and it is hollowed to receive two 40 spring clutches, K and K', which latter clutch, K', is attached to the brace end and serves to hold the wheel J stationary while the clutch K, attached to arm L, is being moved downward or backward in consequence of the projection 45 M, attached to arm L, being struck and moved downward by the screw-threaded pin C³ in its descent, while the sliding tube C is being pressed down.

R² is the felt covering of the roll R, and R' is 50 its axle.

S are arms on the plate T, which support the ends of the axle R' of the paste-roll, and S' a support for the same.

X' is the lower cutter fixed in the frame, and 55 X is the movable cutter attached to the inner side of the back plate, C'.

Z² are automatic plates moving laterally over the guides Z of the frame and supported by wires Z', attached to the sides of frame 60 and provided with the pin Z', against which the lower angle or foot of the rear plate, C', impinges in its descent, forcing the arms out-

ward they direct the slip cut from the ribbon to the paper where it is attached by the presser Y².

The paste-roll R is journaled in the arms S of the plate T, and as the latter is attached to a pivoted or swinging frame, which frame consists of arms U and cross-bars V', and the motion of this frame is regulated by the springs U², it follows that the feed-roll R will be moved away from or approached to the roll I according as the paper ribbon which passes between them is thick or thin, or the roll R can be removed for cleaning by sliding out the plate T from its supports or frame.

Y is an arm attached to the rear plate, C', and Y' is the end of said arm bent at right angles to lift the projection M on the clutch K and return the wheel J to its normal position.

I' is the axle of roller I; P', like axle of paste-cock P².

P² is a clutch which holds paste-cock P² in place.

O² are the corrugations or flutings on the roller O. The object of these corrugations is to keep the roller O from rubbing off the paste from the name-slip as the same passes between the rollers I and O.

N is the support for the main wheel J.

Y² is a presser which is attached to the end of back plate, C', and as the knives or cutters X and X' meet and sever the strip containing an address the presser Y² attaches the same to the paper for which it is designed.

W is a plate or table parallel with the lower knife, X', and immediately in rear of it and in front of the roller O, having a series of flutings, so that the pasted slip will pass over it without having all the paste rubbed off, and W² is a guide, between which and plate W the ribbon is fed to the cutter.

Operation: The paper ribbon is first rolled or wound onto the spool by the handle. The free end is then by reverse motion of the handle carried down through the guide D to the rolls I, R, and O, which will by friction draw it down and paste the under side. Then the sliding tube C is grasped and forced down on

tube B until the lower surface of plate C' strikes the projection on the upper part of frame A, to which said projection the springs U² are attached, and meanwhile the pin C³ strikes the projection M, which is attached to the clutch K on the axle of the main wheel J,

which carries the clutch partly around without moving the wheel. Then the spring C¹ returns the sliding tube C upward to its place, carrying with it the rear plate, C', whose arm Y Y' strikes the lower side of the projection M and partially revolves the wheel J, and with it the several rollers, drawing the printed slip

or ribbon down between the guides W W', where the next downward movement of the sliding tube will cause the knife or cutter X to descend and sever a pasted slip of the ribbon containing an address, and the presser Y² attaches it to the folded paper.

Having thus fully described my invention, what I claim therein as new, and desire to secure by Letters Patent, is—

1. In an addressing-machine, the combination of the fixed tube B with the sliding tube C, the feed-rolls I O, the clutch K, wheel J, and the mechanism for returning the sliding tube to its normal position, all substantially as described.
- 10 2. In an addressing-machine, the combination of the frame A with the fixed tube B, the guide D, the gate Q', the paste-reservoir, and the paste-cock P², all substantially as described.
- 15 3. In an addressing-machine, the combination of the paste-reservoir provided with a gate constructed as described, the paste-cock, and the felt-covered paste-roller with the feed-rolls I and O, all substantially as described.
- 20 4. The combination, in an addressing-machine, of the spool, the guide D, located within the fixed tube B, the paste-reservoir, the paste-gate Q', the paste-cock P², and the felt-covered paste-roll R, all substantially as described.
- 25 5. The combination, in an addressing-machine, of the sliding tube C, the screw-threaded pin C³, the arm L, having projection M, and the drive-wheel J, with means to operate same, as described, and the feed-rolls I and O, all substantially as described.
- 30 6. The combination, in an addressing-machine, of the fixed and sliding tubes with the screw-threaded pin C³, the arm L, having pro-

jection M, the wheel J, the arm Y Y', the feed-rolls I and O, and the mechanism for returning the sliding tube, with its plate and knife attached, to its normal position, all substantially as described. 35

7. The combination, in an addressing-machine, of the sliding tube C, having attached the plate G' and the rear support, C', carrying the cutting-knife X, the fixed knife X', the pin C³, the arm Y Y', the feed mechanism, and the presser Y² for attaching the pasted slip, all 40 45 substantially as described.

8. The combination, in an addressing-machine, of the feed-rolls O and I, the paste-cock P², the paste-roll R, the plate T with its frame, consisting of arms U and cross-bars V', the 50 arms U', and the springs U², all substantially as described.

9. The combination of the wheel J with the feed-rolls I and O, the paste-cock and the series of gear-wheels i, P, and o, and the roll R, 55 all substantially as described.

10. The combination of the movable plate T, the frame U V', and the spring U² with the curved arms U', moving in the slots V, the feed-rolls O and I, and the paste-roll R, all 60 substantially as described.

In testimony whereof I hereto affix my signature in presence of two witnesses.

THEOPHILUS CHARLES EBERHARDT.
